Primary Examiner — Darlington Ly

(57) CLAIM

The ornamental design for a children tricycle, as shown and described.

DESCRIPTION

FIG. 1 is a top-front-right side perspective view of a children tricycle embodying my new design;

FIG. 2 is a top-rear-right side perspective view thereof;

FIG. 3 is a bottom-front-left side perspective view thereof;

FIG. 4 is a right side elevation view thereof;

FIG. 5 is a left side elevation view thereof;

FIG. 6 is a rear elevation view thereof;

FIG. 7 is a front elevation view thereof;

FIG. 8 is a top plan view thereof;

FIG. 9 is a bottom plan view thereof; and,

FIG. 10 is a front-left side perspective view thereof.

The broken lines in the drawing depict portions of the children tricycle that form no part of the claimed design.
